A. J. McCarley.

Inventor:—
Daniel B. Wallace.

By Aigdon Longan Atty.

UNITED STATES PATENT OFFICE.

DANIEL B. WALLACE, OF DECATUR, ILLINOIS.

IRONING-BOARD.

SPECIFICATION forming part of Letters Patent No. 634,741, dated October 10, 1899.

Application filed January 11, 1899. Serial No. 701,858. (No model.)

To all whom it may concern:

Be it known that I, DANIEL B. WALLACE, of the city of Decatur, Macon county, State of Illinois, have invented certain new and useful Improvements in Ironing-Boards, of which the following is a full, clear, and exact description, reference being had to the accompanying drawings, forming a part hereof.

My invention relates to ironing-boards; and it consists of the novel construction, combination, and arrangement of parts hereinafter described and claimed.

Figure 1 is a view in perspective of my improved ironing-board, the same being in position for use. Fig. 2 is a longitudinal sectional view taken approximately on the line 2 2 of Fig. 1. Fig. 3 is a view looking at the under side of the ironing-board, the same being folded for storage or transportation. Fig. 4 is a side elevation of the folded ironing-board.

In the construction of my improved device the board or table 1 is provided with a pointed outer end 2, and in the opposite end of said board is located a plurality of longitudinally-extending slots 3. Immediately in front of these slots 3 and on top of the board 1 is rigidly fixed a transverse cleat 4. Secured to the under side of the board 1 is a pair of cleats 5, the same being positioned between the slots 3, said cleats extending from said slots longitudinally toward the forward end of the board 1.

Pivotedly secured to the under side of the board 1 at each side thereof are the rear ends of swinging arms 6.

7 indicate legs securely framed together adjacent their lower ends, the upper ends of which legs hinge upon a rod 8, passing through the rear ends of the cleats 5, and said legs are extended a slight distance beyond this rod 8 and are provided with the heads 9, having the flat lower faces 10.

A bosom and sleeve ironing-board 11 is provided at its rear end with a pair of lugs 12 and 13, which lugs hinge upon the rod 14, passed directly through the heads 9 of the upper ends of the legs 7.

When my improved ironing-board is in use, the board 1 is brought into a horizontal position with the slotted rear end of said board immediately beneath the edge of the table,

after which the lower ends of the legs 7 are engaged upon the floor, and the outer end of the ironing-board 1 is lowered until the edge 55 of the table is clamped between the flat lower faces 10 of the heads 9 and the upper face of the rear end of said board. The bosom or sleeve ironing-board 11 is swung over onto the table on which the ironing-board is engaged, as seen in Fig. 2, while the ironing board or table 1 is being used, and, if desired, the arms 6 may be swung laterally from their positions beneath the edges of the board or table 1 to sustain the sleeves or any portion 65 of the garment that is being ironed.

When it is desired to use the bosom or sleeve ironing-board 11, the same is swung over onto the ironing board or table 1, the rear end of said bosom-board resting directly 70 upon the transverse cleat 4.

When the ironing-board is folded for storage or transportation, the arms 6 are first swung into longitudinal positions beneath the side edges of the board or table 1, after which 75 the legs 7 are swung upwardly against the under side of the board or table 1, and finally the bosom or sleeve board 11 is swung upwardly to a position immediately beneath the legs 7. When the legs 7 are swung upwardly 80 against the under side of the board or table 1, the body portions of said legs will occupy positions on each side of and between the longitudinally-extending cleats 5. Thus when said board is folded it is very compact and 85 a large number of said boards may be stored in a comparatively small space.

The lugs 12 and 13 are eccentrically pivoted between the heads 9, and when the sleeve-board 11 is swung over into position for use 90 the edge of the table will be clamped between the higher portion of the lugs 12 and 13 and the rear end of the board or table 1.

An ironing-board of my improved construction is simple, strong, and durable, is easily 95 manipulated, and is very efficient in use.

I claim—

In a device of the class described, an ironing-board having a slotted rear end, the transverse cleat 4 arranged on top of said board in front of said slots, a pair of longitudinally-extending cleats fixed to the under side of the board, a plurality of legs framed together and hinged between the rear ends of the lon-

itudinally - extending cleats, the heads 9 formed integral with the upper ends of said legs, which heads are provided with flat lower surfaces, the rear ends of which legs pass upwardly through the slots in the ironing-board, a bosom-ironing board, the lugs 12 and 13 integral with the rear end of said bosom-board, which lugs are eccentrically pivoted between the heads of the legs, and swinging arms ar-

ranged beneath the side edges of the ironing-board, substantially as specified.

In testimony whereof I affix my signature in presence of two witnesses.

DANIEL B. WALLACE.

Witnesses:

M. B. SMITH,

ALBERT J. McCUALEY.
